SLIDING WINDOW

Alexander Herman, Berlin, Germany

Application January 25, 1932, Serial No. 588,784,
and in Germany February 4, 1930

6 Claims. (Cl. 189—72)

My invention relates to sliding windows for use in the ground floors of dwellings and business establishments, the window when lowered being received in a shaft adjoining the cellar. As these windows are constructed of large dimensions, the substantial masses of metal forming the sash conducts away the heat and with a heavy frost the metal parts sweat at the side facing the room.

10 Further, with such arrangements good packing of the closed window, especially at the side next to the cellar, is of particular importance. The warm air at the basement passes very rapidly in winter through untight joints and the room is quickly cooled. Further, with defective packing disagreeable odors readily pass through the shaft.

15 The invention avoids the drawbacks inherent in known constructions.

In the present construction the sliding windows have a metal frame-work carrying the glass-pane, said frame-work having closed insulating chambers along all the sides and edges of said pane which prevent the conduction away of the heat.

20 Secured to the underside of the sash is an intermediate frame also of box formation and partitioned into several air chambers, with or without auxiliary chambers, a frame arranged beneath said intermediate frame forming a chamber 25 acting as an insulating space.

Further details of the invention are herein-after described and illustrated in the accompanying drawing in which Fig. 1 shows diagrammatically the window assembly in cross section.

30 Fig. 2 is a side elevation of the sash.

Fig. 3 is a section on the line III—III of Fig. 2 to a larger scale.

Fig. 4 is a section on the line IV—IV of Fig. 2. Fig. 5 is a section showing the upper part of 40 the window sash in lowered position.

Fig. 6 is a cross-section showing another form of the lower frame member and packing means.

The floor 3 is formed in the plane of the window with a slot 3' which is continued in downward 45 direction as a shaft 4. In the embodiment illustrated it is assumed that the cellar of the house will serve as a shaft into which the window is lowered.

Connected with the lower part of the window 50 sash 2 is a bracket 5 engaged by a rope 5' actuated through gearing by a motor in order to raise and lower the windows mechanically (Fig. 1).

The window pane 1 is fitted in the sash 2 which embraces all four edges of the frame and is of 55 boxlike formation. There are thus provided at

both sides of the plane of the pane cavities 21 which are closed on the street side and on the room side, and also at the faces which bear on the pane and serve as insulating spaces.

At the upper side of the window there is connected with the sash 2 a cross frame 28 which is closed on top by a plate 30 carrying the packing strips 30', which, when, the window is closed, bear against two sealing faces 31 on the transom 29 connected with the masonry with the 60 interposition of filling material.

The upper cross frame 28 is also of box formation so that there results a closed space 28' acting as an insulating air gap.

At both sides there is fixed to the sash 2 an auxiliary frame 32 (Fig. 4) which encloses a cavity 32' acting as an insulating chamber. Connected with the frame 32 is a set of projecting members the middle one 37 of which is of T formation and provided with cranked flanges 75 (Fig. 4). These members are guided in suitable recesses in the lining member 34 fixed to the masonry 35 with the interposition of a filling medium.

This style of guidance ensures easy and exact 80 translatory movement of the window and also tight sealing. The tortuous crevices resembling those presented by labyrinth packings prevent cold air from streaming in from outside.

In the lining member 34 there are also provided closed chambers 33 acting as insulating spaces.

On the underside of the window there is secured to the sash 2 an intermediate frame 6 also of box formation, the cavity of which intermediate frame is partitioned by a wall 24 of wood or other poorly conducting material into two chambers 22, 23 acting as insulating spaces. On the room side or at both sides there is fixed to the auxiliary frame 6 a supplemental frame 95 (Figs. 3 and 6) which forms an auxiliary insulating chamber 7.

A plate 9 connected with the frame 6 serves as an upper closure for a chamber 10 which is bounded by lateral walls 10' and a lower transverse plate 10'' connected with the bracket 5.

At the base of the chamber 10 there are arranged for example between spring contact clips electrical heating resistances 25. To conduct the current there serves a conductor 26 leading to a contact 27 by means of which for example a heating current can be switched on or off from the dwelling room. For the supply of current there may naturally also be used other suitable arrangements; for example, a contact stud may 110

be secured to the lower frame and engage a contact rail mounted in the masonry. If necessary, the contact arrangement may be so devised that in given positions of the window the current is 5 automatically switched on or off, or the current may be switched on or off automatically by a thermostat device.

For packing the window at the slot 3' or in the shaft 4 there serves the following arrangement.

Above the cross plate 9 of the boxlike frame 10 there are provided angle bars 8 which project at both sides above the frame. In the space bounded by the vertical flanges of the angle 15 bars 8 (Fig. 3) there are fitted at both sides grooved packing strips 11 of rubber or the like. Additional angle irons 12 serving as carriers for packing tubes 13 are connected with the lateral walls 10' of the box frame 10.

The slot 3' is lined on both sides with bars 14 which each merge on top into a T-piece 16. One limb of the T-piece projects over the slot 3' and is provided on the upper side with an inclined face 15 which facilitates the running off of water. The T-piece 16 has a downward projection 16' (Figs. 3 and 5) or an inclined face 16'' (Fig. 6).

When the window is closed, that is, raised, the rubber packings 11 engage the projections 16' of the bars 14. Further, at the same time the tubular packings 13 bear against the inclined faces 17 of the bars 14.

In this way there are formed on both sides closed insulating chambers 20 of which each is bounded by the outer walls of the bar 14, by the wall 10' of the frame 10, and on top and bottom by the packings 11 and 13. These insulating chambers prevent exchange of air and heat between the room closed by the window and the 40 shaft or cellar.

In the modified construction according to Fig. 6 each T-piece 16 is provided with an inclined face 16''. The plate 9 has laterally projecting parts 18 upon which rest carriers 19 for the packing tubes 21. In the raised or closed position of the window these tubes are pressed against the faces 16''. The arrangement of the lower packings 13 is the same as in the construction according to Fig. 3. In this case also in the closed 50 position of the window closed insulating chambers are formed by the double packing at both sides of the window, which chambers pack the window reliably from the underside and prevent draughts and penetration of odors from the cellar.

In the construction according to Fig. 6 the boxes 7 have projections which are inclined in correspondence with the packing faces 16'' and which act as a stop on lifting the window.

The bars 14 also insulate the chambers 20 relatively to the masonry. They overlap the sill at the outer side and close the slot 3' at the inner side so that between them and the masonry auxiliary insulating chambers 14' are provided.

With the window fully open the plate 30 bears against the T-shaped projections 16 of the bars 14 as shown in Fig. 5, so that the shaft is covered.

I claim:

1. A sliding window comprising a metal sash carrying the glass pane, said sash being of box formation and having cavities forming closed insulating chambers at both sides of the pane, an intermediate frame also of box formation secured to the underside of said sash, and providing further closed insulating chambers 145

bers underneath said sash and said pane, electrical heating resistances fitted within the chamber of said lower frame, and electrical connections leading outside of said chamber for providing current to said heating resistances.

2. In combination with a sliding window comprising a metal sash carrying the glass pane, a slot in the floor, lining bars arranged at both sides of said slot, said sash being of box formation and having cavities forming closed insulating chambers at both sides of the plane of the pane, an intermediate frame also of box formation secured to the underside of said sash, and providing further closed insulating chambers underneath said sash and said pane, electrical heating resistances fitted within the chamber of said lower frame, electrical connections leading outside of said chamber for providing current to said heating resistances, two spaced packing faces arranged on each of said lining bars, yielding faces provided on both sides of said lowermost frame, said packing faces cooperating with said yielding faces in the closed position of the window to afford at both sides of said lowermost frame insulating chambers closed all round.

3. In combination with a sliding window comprising a metal sash carrying the glass pane, a slot in the floor, lining bars arranged at both sides of said slot, said sash being of box formation and having cavities forming closed insulating chambers at both sides of the plane of the pane, an intermediate frame also of box formation secured to the underside of said sash, and providing further closed insulating chambers underneath said sash and said pane, electrical heating resistances fitted within the chamber of such lower frame, electrical connections leading outside of said chamber for providing current to said heating resistances, two spaced packing faces arranged on each of said lining bars, yielding faces provided on both sides of said lowermost frame, said yielding faces mounted on spaced supports projecting laterally from said lowermost frame, said packing faces consisting of upper and lower abutment rails provided on said lining bars and engaging said yielding faces in the closed position of the window to afford at both sides of said lowermost frame insulating chambers closed all round.

4. In combination with a sliding window comprising a metal sash carrying the glass pane, a slot in the floor, lining bars arranged at both sides of said slot, said sash being of box formation and having cavities forming closed insulating chambers at both sides of the plane of the pane, an intermediate frame also of box formation secured to the underside of said sash, and providing further closed insulating chambers underneath said sash and said pane, electrical heating resistances fitted within the chamber of said lower frame, electrical connections leading outside of said chamber for providing current to said heating resistances, two spaced packing faces arranged on each of said lining bars, yielding faces provided on both sides of said lowermost frame, said packing faces cooperating with said yielding faces in the closed position of the window to afford at both sides of said lowermost frame insulating chambers closed all round, said lining bars overlapping the upper edges of said slot and having downwardly projecting portions affording additional insulating chambers at both sides of said slot.

5. A sliding window adapted for insertion in an opening in masonry comprising a metal sash

carrying the glass pane, said sash being of box formation and having cavities forming closed insulating chambers at both sides of the plane of the pane, an intermediate frame also of box formation secured to the underside of said sash, and providing further closed insulating chambers underneath said sash and said pane, auxiliary frames fixed to the vertical edges of said sash, each of said auxiliary frames comprising a closed insulating chamber located edgewise to said pane, lining members adapted to be fixed to the masonry adjacent to both vertical edges of said sash, projecting members on said auxiliary frames, and recesses in said lining members for forming labyrinth-like packings, said lining members comprising closed cavities forming further insulating chambers. 80

5 6. A sliding window adapted for insertion in an opening in masonry comprising a metal sash carrying the glass pane, said sash being of box formation and having cavities forming closed insulating chambers at both sides of the plane of the pane, an intermediate frame also of box formation secured to the underside of said sash, and providing further closed insulating chambers underneath said sash and said pane, auxiliary frames fixed to the vertical edges of said sash, each of said auxiliary frames comprising a closed insulating chamber located edgewise to said pane, lining members adapted to be fixed to the masonry adjacent to both vertical edges of said sash, projecting members on said auxiliary frames, and recesses in said lining members for forming labyrinth-like packings, said lining members comprising closed cavities forming further 85 insulating chambers. 90
